UNITED STATES PATENT OFFICE.

JAHN JASUS, OF STREATOR, ILLINOIS.

COMBINED TABLE AND IRONING-BOARD.

1,100,887.

Specification of Letters Patent. Patented June 23, 1914.

Application filed January 2, 1914. Serial No. 809,905.

To all whom it may concern:

Be it known that I, JAHN JASUS, a subject of the Emperor of Austria-Hungary, residing at Streator, in the county of LaSalle and State of Illinois, have invented certain new and useful Improvements in Combined Tables and Ironing-Boards, of which the following is a specification.

This invention relates to certain new and useful improvements in a combined table and ironing-board.

An object of the invention is to provide a kitchen table with an ironing-board that is adapted to slide inwardly and outwardly of the table and in its innermost position is adapted to lie under the top of the table and be completely concealed from view.

A further object of the invention is to provide a table with an ironing-board adapted to be slid inwardly and outwardly thereof and be effectively held in either of its extreme positions.

With the above and other objects in view which will appear as the nature of the invention is better understood, the same consists in the novel construction, combination and arrangement of parts to be hereinafter more fully described and then claimed, reference being had to the accompanying drawing by like characters throughout the several views, and wherein:

Figure 1 is a side elevational view of my combined table and ironing-board, with the ironing-board in extended or operative position. Fig. 2 is a bottom plan view of the same with the ironing board in retracted position. Fig. 3 is a longitudinal sectional view of the same. Fig. 4 is an enlarged transverse sectional view, and Fig. 5 is an enlarged longitudinal sectional view of a portion of the table, illustrating the manner of supporting the inner end of the ironing-board when the same is in extended position.

Referring more specifically to the drawing, the reference numeral 10 indicates a table top supported upon the legs 11 of usual construction and connected to the legs 11 to assist in supporting the table top 10 are the side frames 12 and end frames 13 and 14 respectively. Suitably secured to the under face of the top 10 are the spaced angle bars or guide rails 10' for the ironing-board to be hereinafter described. The end frame 13 is provided with a cut-away portion for purposes to be hereinafter described and this

cut-away portion is suitably stepped as at 15, as best seen in Fig. 4.

An ironing-board is adapted to slide inwardly and outwardly relative to the table through the opening provided in the end frame 13 and this ironing-board is designated 16. A hand-hold device 17 is carried by the outer end of the board and assists in sliding the same inwardly and outwardly. The inner end of the board is provided with a similar member 18 which constitutes means to limit the inward movement of the board. A leaf hinge has one of its leaves 19 suitably connected to the under face of the ironing board 16 adjacent the outer end 70 thereof, while the other leaf 20 of said hinge is suitably connected to an ironing-board support or leg 21. The leg 21 is provided adjacent each end thereof with an eye-bolt 22. A resilient hasp member 23 is pivoted as at 24 to the under side of the ironing-board and is adapted to be moved to cause its hooked end to engage either of the eye-bolts 22.

Connected to the under face of the ironing-board adjacent the inner end thereof is a resilient member 25. The member 25 is substantially V-shaped and has its upper ends slotted as at 26, through which the securing bolts 27 pass in entering the ironing-board 16. The lower end of the member 25 is preferably provided with a slight bent up portion 28 to engage the end frame 13 and be effectively retained in such position.

In the position shown in Fig. 1 the ironing-board is moved outwardly from the table and guided by the rails 10' and the swinging hasp 23 engages one of the eye-bolts 22, thereby locking the leg 21 in a vertical position. The inner end of the ironing-board when the same is in its extended position is clearly shown in Fig. 5. As shown in said figure, the resilient member 25 has its lower end 28 engaging the lower wall of the opening provided in the end frame 13. Resiliency is added to the member 25 by its slotted connection 26 and 27 with the ironing-board 16. To cause the ironing-board to assume the position shown in Fig. 2 the swinging hasp 23 is released from one of the eye-bolts 22 and swung on its pivot in an inward direction whereupon the leg 21 is swung upwardly and the hooked end of the hasp engages in the other of said eye-bolts 22 and holds the leg in a position.

substantially parallel with the ironing-board 16. Slight pressure upon the outer end as at 17 will release the resilient member 25 from the end frame 13 whereupon the said 5 board may be slid inwardly and limited in such movement by the member 18 upon the inner end thereof engaging the opposite end frame 14.

While I have shown and described the 10 preferred embodiment of my invention, I do not wish to confine myself thereto, as various forms, modifications and arrangements of the parts as shown may be had without departing from the spirit and scope 15 of the invention as claimed.

I claim:—

The combination with a table having parallel end bars, one of which is provided with an opening, of parallel longitudinally-dis-

posed confronting angle bars secured to the 20 under side of the table-top, an ironing board slidably supported on said angle bars, a leg hinged at one end to said board, and provided adjacent to each of its ends with an eye, a hasp pivotally-secured at one end to 25 the underside of said board, and having a hook at its opposite end adapted to engage either of said eyes, and a resilient securing device depending from said board and provided with a bend to engage one of the walls 30 of said opening.

In testimony whereof I affix my signature in presence of two witnesses.

JAHN JASUS.

Witnesses:

JOHN ANTOLIK,
THOMAS BUNDY.
